Primary Examiner — Catherine S Posthauer*Assistant Examiner* — Christine Marie Achen Zimmerman(74) *Attorney, Agent, or Firm* — Dickinson Wright PLLC(57) **CLAIM**

The ornamental design for a cutting board as shown and described.

DESCRIPTION

FIG. 1 is a top, perspective view of a cutting board, showing my new design;

FIG. 2 is a top view thereof;

FIG. 3 is a rear view thereof;

FIG. 4 is a right side view thereof;

FIG. 5 is a front view thereof;

FIG. 6 is a left side view thereof;

FIG. 7 is a bottom view thereof; and,

FIG. 8 is a bottom perspective view thereof.

The broken lines in the figures depict portions of the cutting board that form no part of the claimed design.

1 Claim, 6 Drawing Sheets(56)
